Attorney

UNITED STATES PATENT OFFICE.

JOHN A. BRILL, OF PHILADELPHIA, PENNSYLVANIA.

DESIGN FOR A TRUCK SIDE BAR.

SPECIFICATION forming part of Design No. 22,920, dated November 28, 1893.

Application filed October 10, 1893. Serial No. 487,776. Term of patent 14 years.

To all whom it may concern:

Be it known that I, JOHN A. BRILL, a citizen of the United States, residing at Philadelphia, in the county of Philadelphia and State of Pennsylvania, have invented and produced a new and useful Design for a Truck Side Bar, of which the following is a specification.

My invention has relation to the design for a truck side bar, the essential feature of which is its configuration.

In the drawings Figure 1 is a side elevation of the side bar; Fig. 2, a plan view thereof; Fig. 3, an end elevation, and Figs. 4, 5, 6, sectional elevations on the lines $y-y$, $x-x$, and $z-z$, Fig. 1, in the order named.

The bar is practically rectangular in shape in side elevation, and comprises the top bar 1, slightly arched, the bottom bar 2, both bars having the vertical bars or transoms 3 extending between them, between which and on top of the metal of the bottom bar 2 is an outwardly extending annular cup or flange 4. Between the bars 1, 2, 3 are substantially rectangular spaces 5, 6. At each end are inverted U shaped parts comprising the vertical cheeks 7, 8 connected at the top by the top bar extension 9, all of which form a yoke, the bottom being open and the top provided

with lugs or projections 10 which increase the diameter of the web of the metal at this point. 30 From the cheeks 8 extend outwardly short arms 11 which have recesses 12 on the outside. By reference to Figs. 1 and 2 it will be seen that the top bar 1 is wider than the arms 11, and by referring to Figs. 4, 5, 6 it will be 35 seen that the bottom bar 2 is narrower than the top bar 1. The outer face of the webs 8 at the lower portion are recessed as at 13 to bring 40 the metal in the same plane as the bottom bar 2, the metal of which extends to the inner face of the yoke as at 14. See Figs. 1, 3, 5.

The whole frame presents an unbroken and continuous configuration in all its parts, which 45 is one of the essential features of this design.

I claim—

The design for a truck side bar, substantially as herein shown and described.

Signed at Philadelphia, in the county of 50 Philadelphia and State of Pennsylvania, this 3d day of October, 1893.

JOHN A. BRILL.
